VALVE FOR ROCK DRILLS

Filed Dec. 23, 1929.

UNITED STATES PATENT OFFICE

WILLIAM A. SMITH, JR., OF PHILLIPSBURG, NEW JERSEY, ASSIGNOR TO INGERSOLL-RAND COMPANY, OF JERSEY CITY, NEW JERSEY, A CORPORATION OF NEW JERSEY

VALVE FOR ROCK DRILLS

Application filed December 23, 1929. Serial No. 416,133.

This invention relates to rock drills, but more particularly to a distributing valve for fluid actuated rock drills of the hammer type.

A few of the objects are to obtain a rapid and positive action of the valve and to assure a heavy blow of the hammer piston against the working implement.

Other objects will be in part obvious and in part pointed out hereinafter.

10 In the accompanying drawings illustrating the invention and in which similar reference characters refer to similar parts,

Figure 1 is a sectional elevation of a rock drill constructed in accordance with the practice of the invention and showing the valve in the position which it will assume at the beginning of the working stroke of the piston, and

Figure 2 is a similar view showing the 20 valve in the reverse position.

Referring more particularly to the drawings, A designates a cylinder having a piston chamber B in which is disposed a reciprocating hammer piston C. The cylinder A has 25 a free exhaust port D which is controlled by the piston C.

A closure is provided for the front end of the piston chamber B in the form of a front cylinder washer E which also serves to centralize a front head F with respect to the cylinder A.

In the front head F is a bore G to receive the shank of a working implement H which extends into a cavity J in the back head F to receive the blows of the hammer piston C. Such blows are in this instance transmitted to the working implement H by an anvil block K disposed slidably in the front cylinder washer E.

40 In the rear end of the cylinder A is a valve chest L comprising a pair of plates O and P. The plate O is seated adjacent the rear end of the piston chamber B for which it forms a closure and supports the plate P. Seated 45 upon the plate P is a back head Q which forms a closure for the rear end of the cylinder A and may be secured thereto in any suitable manner.

The back head Q serves as a housing for 50 a rotary throttle valve R having a chamber

S into which pressure fluid may be constantly admitted from a suitable source of supply. In the wall of the throttle valve R is a port T to register with a passage U in the back head Q and which passage opens into a supply reservoir V also in the back head Q.

55 Within the plate P is a bore to form a valve chamber W adapted to accommodate a distributing valve X for which the plate O forms a seat. The valve chamber W comprises an enlarged portion Y and a reduced portion Z. The pressure fluid intended to be distributed by the valve X is in this instance introduced into the enlarged portion Y and conveyed thereto by a supply passage b which 60 communicates with the supply reservoir V.

65 At the juncture of the enlarged portion Y and the reduced portion Z of the valve chamber W is an annular groove c from which leads a front inlet passage d having its outlet opening at the front end of the piston chamber B. The pressure fluid utilized for driving the piston C forwardly against the anvil block K is admitted into the rear end 70 of the piston chamber B by rear inlet passages e in the plate O.

75 The valve X comprises a stem f which extends slidably into the reduced portion Z, and a flange g at the front end of the stem f lies within the enlarged portion Y and is 80 preferably of somewhat smaller diameter than said enlarged portion so that the pressure fluid will flow over the edge of the flange to the rear inlet passage e.

85 The front end of the flange g constitutes a pressure surface h which is intermittently exposed to compression from the rear end of the piston chamber B for throwing the valve X rearwardly. On the rear end of the flange g is a constant pressure surface j of smaller 90 area than the pressure surface h and against which pressure fluid constantly acts to throw the valve forwardly.

95 Additional means are provided to assist in throwing the valve forwardly. To this end the stem f of the valve is provided with an actuating and holding surface k which is intermittently exposed to pressure fluid to assist the pressure acting against the pressure surface j to throw the valve forwardly. The 100

pressure fluid utilized for this purpose is admitted into the rear end of the reduced portion *Z* of the valve chamber by a passage *o* which communicates at its inlet opening 5 with the inlet passage *d*.

In order that the piston *C* may strike a heavy blow against the anvil block *K* and thus to the working implement *H* unhampered by compression in the front end of the piston 10 chamber *B*, the valve stem *f* is provided with a reduced portion or neck *p* around which compression may flow from the front inlet passage *d* to a vent *q* leading from a point intermediate the ends of the reduced portion 15 *Z* to the atmosphere.

The operation of the device is as follows: With the valve *X* and the cylinder *A* in the rearmost positions illustrated in Figure 1, pressure fluid entering the enlarged portion 20 *Y* of the valve chamber *W* from the supply passage *b* will flow over the edge of the flange *g* through the front end of the valve chamber and through the rear inlet passages *e* into the rear end of the piston chamber *B* to drive the 25 piston *C* forwardly against the anvil block *K*. Shortly after the piston *C* starts on its forward stroke, it will cover the exhaust port *D* and the air in the front end of the piston chamber *B* will then be expelled therefrom 30 through the inlet passage *d* and around the neck *p* of the valve, thence through the vent *q* to the atmosphere. In this way a heavy uncushioned blow will be struck by the piston against the anvil block.

35 Shortly prior to the impact of the hammer piston *C* against the anvil block the rear end of the piston *C* will uncover the exhaust port *D* so that the pressure fluid utilized for impelling the piston *C* forwardly will be exhausted to the atmosphere. This will cause 40 a drop in pressure forwardly of the pressure surface *h*. The pressure acting against the pressure surface *j* will then start the valve forwardly.

45 Upon the unseating of the valve pressure fluid will flow into the inlet passage *d* and thus also through the passage *o* into the rear end of the reduced portion *Z* of the valve chamber. There it will act against the surface *k* to assist the pressure fluid acting against the pressure surface *j* to complete the forward movement of the valve *X* and also to hold the valve in its foremost position. The pressure fluid thus admitted into the 50 front end of the piston chamber *B* will return the piston *C*. The air in the rear end of the piston chamber *B* will then be compressed by the piston and such compression will act against the pressure surface *h* to raise the 55 valve *X* again to its initial position, thus completing the cycle of operations.

I claim:

1. In a fluid actuated rock drill, the combination of a cylinder and a piston therein, 60 a valve chest having a valve chamber, front

and rear inlet passages leading from the valve chamber to the ends of the cylinder, a distributing valve in the valve chamber to control the inlet passages and comprising a stem, a flange on the stem to control the 70 inlet passages and around which pressure fluid flows to the rear inlet passage, a pressure surface on the flange intermittently exposed to compression from the rear end of the cylinder to throw the valve for opening the rear inlet passage, a constant pressure surface on the other end of the flange constantly exposed to pressure fluid tending to throw the valve for opening the front inlet passage, an actuating surface on the stem, 80 and a passage in the valve chest for intermittently conveying pressure fluid from the front inlet passage to the actuating surface to assist the pressure fluid acting against the constant pressure surface in throwing the 85 valve and to hold the valve momentarily stationary.

2. In a fluid actuated rock drill, the combination of a cylinder and a piston therein, a valve chest having a valve chamber, front 90 and rear inlet passages leading from the valve chamber to the ends of the cylinder, a distributing valve in the valve chamber to control the inlet passages and comprising a stem, a flange on the stem to control the inlet 95 passages and around which pressure fluid flows to the rear inlet passage, a pressure surface on the flange intermittently exposed to compression from the rear end of the cylinder to throw the valve for opening the rear inlet passage, a constant pressure surface on the other end of the flange constantly exposed to pressure fluid tending to throw the valve for opening the front inlet passage, an actuating surface on the stem, a passage in 100 the valve chest for intermittently conveying pressure fluid from the front inlet passage to the actuating surface to assist the pressure fluid acting against the constant pressure surface in throwing the valve and to hold the valve, a vent leading from the valve chamber to the atmosphere, and a neck on the stem around which compression flows from the 105 front inlet passage to the vent.

In testimony whereof I have signed this 115 specification.

WILLIAM A. SMITH, JR.
